(57) **CLAIM**

The ornamental design for a suction stabilizer for minimally invasive off-pump bypass surgery, as shown and described.

DESCRIPTION

FIG. 1 is a top perspective view of a suction stabilizer for minimally invasive off-pump bypass surgery embodying our design with a bendable shaft at a first orientation.

FIG. 2 is a top plan view thereof with the bendable shaft at the first orientation.

FIG. 3 is a bottom plan view thereof with the bendable shaft at the first orientation.

FIG. 4 is a side elevational view thereof with the bendable shaft at the first orientation.

FIG. 5 is a side elevational view thereof with the bendable shaft at the first orientation.

FIG. 6 is a front elevational view thereof with the bendable shaft at the first orientation.

FIG. 7 is a rear elevational view thereof with the bendable shaft at the first orientation.

FIG. 8 is a bottom perspective view thereof with the bendable shaft at the first orientation.

FIG. 9 is a side perspective view of a suction stabilizer for minimally invasive off-pump bypass surgery embodying our design with a bendable shaft at a second orientation.

FIG. 10 is a front elevational view thereof with the bendable shaft at the second orientation.

FIG. 11 is a rear elevational view thereof with the bendable shaft at the second orientation.

FIG. 12 is a side elevational view thereof with the bendable shaft at the second orientation.

FIG. 13 is a side elevational view thereof with the bendable shaft at the second orientation.

FIG. 14 is a top view thereof with the bendable shaft at the second orientation.

FIG. 15 is a bottom view thereof with the bendable shaft at the second orientation; and,

(Continued)

FIG. 16 is a bottom perspective view thereof with the bendable shaft at the second orientation.
